UNITED STATES PATENT OFFICE.

FRANK D. ARNOLD, OF HUMBOLDT, IOWA.

PHONOGRAPH.

Application filed May 24, 1921. Serial No. 472,058.

This invention relates to phonographs, and more specifically to an improved megaphone or sound amplifier for use in connection with phonographs.

5 One object of this invention is to greatly increase the volume of sound directed into the megaphone, while preserving tone and melody.

A further object is to provide an improved 10 megaphone of this character which can be applied either internally or externally of a phonograph cabinet, and is attachable to phonographs of different kinds and sizes.

15 A further object is to provide a combination of strings, bridges, sounding posts and sounding bars in connection with a megaphone, for improving the effects of the megaphone, by equalizing or balancing the tone.

20 Other objects and advantages will be pointed out or implied in the following details of description, in connection with the accompanying drawings in which:—

Fig. 1 is a front view of a cabinet-phonograph including a megaphone constructed in accordance with the present invention, a portion of the cabinet being omitted.

25 Fig. 2 is a vertical sectional view of the cabinet-phonograph shown in Fig. 1, the sections of the cabinet and megaphone being taken in different planes, the front end of the megaphone being a full side elevation.

30 Fig. 3 illustrates a modified form of megaphone in connection with a horn or sound passage of an ordinary phonograph.

35 Figure 4 is a front elevation of another modified form, in which the inner and outer horns are polygonal in cross sections.

Fig. 5 illustrates another modified form of polygonal megaphones.

40 Fig. 6 is a side elevation of a modified form of sounding bar.

Referring to these drawings in detail, in which similar reference characters correspond with similar parts throughout the several views the invention consists in the construction, arrangement and combination of parts, as will now be fully described as follows:

45 Referring to Figs. 1 and 2, a phonograph cabinet is indicated at 10, the same being provided with a doorway or front opening 11 the door being omitted, although a door may be provided for closing the opening 11. The motor-box is indicated at 12; the record-table, at 13; the sound-arm, at 14; and the reproducer, at 15.

The sound-arm communicates in the usual manner with the interior of the cabinet, and constitutes a portion of the sound passage, the remaining portion of the sound passage 60 being indicated at 16. This tubular body 16 communicates with the interior of a horn or megaphone 17, the latter having its rear end fitted in that of an outer megaphone 18. The front end of the outer megaphone ex- 65 tends a considerable distance beyond the front end of the inner megaphone. In other words, the inner megaphone extends forward in the outer megaphone and terminates in the intermediate portion of the latter, so 70 that when the sound-waves pass from the inner megaphone, they are received by the outer megaphone and thereby amplified or intensified. The forward and major portions of the inner megaphone are spaced 75 from the outer megaphone, and sound-posts 19 extend from the inner to the outer megaphones so as to hold them in their spaced relation and also assist in amplifying the sound.

80 A series of bridges or sounding bars 20 is arranged around the external periphery of the outer megaphone, preferably adjacent to the front ends; although it is within the scope of this invention to place the bridges 85 at any preferred position on the inner or outer megaphone, or upon any single megaphone. Any appropriate number of music-strings 21 are supported on the bridges 20, and these strings can be stretched to any 90 degree of tautness by any appropriate means, so as to properly attune. At 22 I have indicated one means of stretching or attuning, this means including a plate 23 which is secured on the outer megaphone 18 95 and provided with tuning pins, lock nuts 24 being provided to secure the tuning pins in adjusted position. However, it is within the scope of this invention to support the tuning pins by means other than the megaphone.

100 Referring now to Fig. 3, a horn of an ordinary phonograph is indicated at 25. The rear end of the inner megaphone 17^a extends into the front end of the horn 25, and a band of felt or rubber may be provided, as indicated at 26, to provide an air tight joint between the horns 25 and 17^a, thus preventing any harsh or rattling sounds to be caused by the attachment of the megaphone to the horn 25. The outer megaphone 18^a has its rear ends fitted around

that of the inner megaphone and secured by any appropriate means; and at the junction of the outer and inner megaphones I may provide any appropriate supporting means, such (for instance) as indicated at 27. The supporting arm 27 may be provided with an opening 28 through which a string, hook, rod or other support can be passed. The arm 27 is bent forward so that the aperture 10 28 is substantially over the center of gravity of the megaphone, and when suspended from the arm 27, the megaphone assumes the position illustrated in Fig. 2. The bridges 20 and 20^a may be of any appropriate form, 15 height, etc., according to the shape and size of the megaphone on which they are seated. Moreover, there may be any appropriate number of such bridges as illustrated in Figs. 1 and 2, eight of the bridges are seated 20 on a megaphone which is circular in cross section, and in Fig. 3, six of such bridges are seated on a circular megaphone (three of the six bridges being on the half section which is not shown).

25 Figs. 4 and 5 illustrate how the music strings 21 are applied on the angles or corners of the megaphone which are polygonal in cross section, that is, on bridges 20^b which are notched at their bases so as to straddle 30 the corners 29 which are formed by the meeting edges of the angular plates which form the outer megaphone.

In Fig. 3 is shown two series of sounding 35 bars 32, in the inner and outer megaphones, respectively. These sounding bars may be plain and of wood, metal or other appropriate material; or they may each be of combined materials as shown in Fig. 6 where the bar 32 has an appropriate music-string 40 33 stretched thereon and a bridge 34 which is mounted on the bar 32. Although I have shown the sounding bars adjacent to the sounding posts and bridges, and in only one figure of the drawings, it is obvious that 45 they are applicable to other parts of the megaphones, either internal or external or both, of any or all embodiments of my invention.

50 Although I have shown the sounding posts 19 positioned midway between the corners 29, it is within the scope of this invention to place the sounding post in any desired position between the inner and outer megaphones. In Fig. 4 the outer megaphone is indicated 55 at 18^b, and the inner megaphone at 17^b, the rear ends of these megaphones being united where indicated by dotted lines at 30. Likewise, in Fig. 5, the outer megaphone 18^a and inner megaphone 17^a are united where 60 indicated by dotted lines at 30. The major portions of the inner and outer megaphones in all forms of the invention, are spaced from one another and provided with sounding posts 19.

65 It is not intended to limit this invention

to the exact construction and arrangement of parts as described and illustrated, but changes may be made within the scope of the inventive ideas as claimed.

What I claim as my invention is:

1. The combination of a horn, bridges on the exterior of said horn, and musical strings stretched on said bridges, each string extending transversely substantially around the exterior of said horn.

2. The combination of a horn, a second horn having its rear smaller end fitted closely in that of the first horn and projecting forward, the forward and major portions of the inner horn being spaced from the interior surface of the outer horn, and sounding posts extending from the outer horn to the inner horn.

3. The combination of a horn, bridges on the exterior of said horn, and resonant strings stretched on said bridges, each string extending transversely substantially around the exterior of said horn, a second horn having its rear end secured in that of the first horn and having its forward and major portions spaced from the outer horn and connected therewith by means of sounding posts.

4. A horn structure comprising inner and outer horns, bridges associated with one of said horns, and music strings spread on the bridges and extending transversely of the horn carrying the bridges.

5. In a phonograph having a cabinet provided with a sound passage, and having a front opening; the combination of a horn in said cabinet having its rear end in communication with said sound passage, said horn extending toward said opening, a series of bridges extending around and seated on the exterior of said horn, and a musical string stretched on said bridges and extending substantially around the periphery of said horn.

6. The combination of a pair of horns, bridges on one of the horns, musical strings stretched around one of said horns and supported by said bridges, and sounding posts connecting said horns so the vibrations of one horn will be transmitted to the other.

7. In a sound amplifying horn, an outer tapering horn and an inner tapering horn, the latter fitting tightly within the smaller end of the former and extending forwardly toward the larger end thereof, sound posts interposed between and connecting the said horns so that vibrations of one horn are transmitted to the other, bridges mounted on one of the horns and resonant strings stretched taut on said bridges.

8. In a sound amplifying horn, an outer tapering horn and an inner tapering horn, the latter fitting tightly within the smaller end of the former, and extending forwardly toward the larger end thereof, bridges

mounted on one of the horns, and resonant strings stretched taut on said bridges.

9. In a sound amplifying horn, an outer tapering horn and an inner tapering horn, the latter fitting tightly within the smaller end of the former and extending forwardly toward the larger end thereof, bridges arranged transversely around the larger end of the horn, and resonant strings, stretched taut on said bridges and extending transversely around said larger end.

10. In a sound amplifying horn, an outer tapering horn and an inner tapering horn, the latter fitting tightly within the smaller end of the former and extending forwardly toward the larger end thereof, sound posts interposed between and connecting the said horns so that vibrations from one horn are transmitted to the other, bridges arranged transversely around the larger end of the horn and resonant strings stretched taut on said bridges and extending transversely around said larger end.

11. In a structure of the character described, an amplifying horn, bridges spaced around the mouth thereof, resonating strings extending transversely around the horn and resting on the bridges, pin supporting means mounted on the horn, and tuning pins mounted and movable in the supporting means.

12. In a sound amplifier, in combination, a pair of substantially co-axial tapering horns, the main portion of one being contained within the other and the two closely inter-fitting adjacent their smaller ends and resonating members carried by the larger end of one of said horns.

13. In a sound amplifier, in combination, a pair of substantially co-axial tapering horns, the main portion of one being contained within the other and the two closely interfitting adjacent their smaller ends, and sounding posts around the larger end of the

inner horn, said posts connecting the two horns.

14. In a sound amplifier, in combination, a pair of substantially co-axial tapering horns, the main portion of one being contained within the other and the two closely inter-fitting adjacent their smaller ends, the free end of the outer horn extending some distance beyond the free end of the inner, so that part of the sound waves emitted at the free end of the inner may strike the outer and cause vibration thereof, and resonating means carried by the free end of said outer horn.

15. In a structure of the character described, an amplifying horn, bridges spaced around the mouth thereof, resonating strings extending transversely around the horn and resting on the bridges, an inner horn spaced from the outer horn and connected therewith by posts to cause simultaneous vibration of the two horns and the strings.

16. A horn structure comprising inner and outer horns, bridges associated with one of said horns, musical strings stretched on the bridges and extending transversely of the horn carrying the bridges, and posts connecting the horns for transmission of vibrations from one to the other.

17. In a structure of the character described, having a cabinet open on one side and having a sound opening in another side, the combination of a tapered horn in said cabinet having its smaller end connected to the sound opening, bridges arranged longitudinally of the horn and placed peripherally around the larger end thereof, and resonator strings resting upon said bridges and cooperating therewith and with the horn to amplify sound vibrations passing therethrough.

In testimony whereof I affix my signature.

FRANK D. ARNOLD.
